UNITED STATES PATENT OFFICE.

ROBERT B. TUNNICLIFFE, OF GRAND RAPIDS, MICHIGAN.

HOSE-SUPPORTER CLASP.

No. 918,398.

Specification of Letters Patent.

Patented April 13, 1909.

Application filed September 7, 1906. Serial No. 333,733.

To all whom it may concern:

Be it known that I, ROBERT B. TUNNICLIFFE, a citizen of the United States, residing at Grand Rapids, in the county of Kent and State of Michigan, have invented new and useful Improvements in Hose-Supporter Clasps, of which the following is a specification.

My invention relates to that class of hose supporters designed to hold the fabric with an elastic or yielding grip, and its particular object is to provide such an elastic or yielding grip in an especially convenient, efficient and economical form. This object is obtained by the construction shown in the drawings.

In these drawings, Figure 1 is a top plan view of the device in completely operative position. Fig. 2 is a longitudinal side view of the same. Fig. 3 is a vertical cross section on the line $x-x$ of Fig. 1, looking in the direction of the arrow. Fig. 4 is a detailed view of the spring clasp which forms a part of the device, and Fig. 5 is a top plan view of the blank from which the cap is formed.

In the drawings the numeral 1 indicates the strap, preferably of nonelastic web, to which the supporter is attached; 2 is the upper plate forming the base to which the spring clasp is attached, and slotted as shown in Figs. 1 and 2 to permit the non-elastic web or strap to pass therethrough. This arrangement permits the plate with attached spring clasp to be adjusted longitudinally upon the strap in the proper position, and it may then be sewed, or otherwise suitably attached to the strap.

3 represents the lower plate which I also prefer to attach to the strap 1, by passing the latter through slots in the plate and then sewing or otherwise permanently fastening it. This keeps the upper and lower plates with their attached parts in proper relative position, ready for use.

4 is the head of the binding post 15 of metal or other suitable material. This post is at its base, permanently and rigidly attached in any suitable manner to the plate 3, so that it projects upwardly at right angles to the plane of the plate.

A cap 6 of metal or other suitable material is suitably shaped or struck up and turned over the loop of the spring catch in the manner shown in Figs. 1 and 2, the blank from which this cap is made being illustrated

by Fig. 5. This cap may be secured in position in any suitable manner.

By reference to Fig. 5 it will be seen that the body of the blank has at one end a lug or projection 5', the remaining portion of the blank being made in double form and adapted to be centrally bent upon itself. The bent connection between the arms 7 and 8 of the clasp is inserted within the double portion of the cap 6 and secured, and when the cap is so applied, the lug or projection 5' is between the portions of the said arms or will extend upwardly when the hose supporter or clasp as an entirety is applied in operative position. On the external surface of this lug 5' I attach in any suitable manner the elastic cushion pad or covering 5. I find that a convenient and efficient means of providing such cushion covering is to vulcanize a soft rubber covering upon the metal base formed by the lug, so that it will be completely covered by this rubber cushion and the two will be permanently attached together. The more essential feature is however, that the outer portion of the lug which comes in contact with the binding post shall be covered by, and shall carry, such elastic cushion.

7 and 8 are the two arms of the continuous spring clasp, made of spring wire or some similar material, and which conveniently may be constructed by coiling the wire upon itself so as to make a spring coil at one end as shown in Fig. 4. The free end of the arm 7 is attached to the plate 2, at or near one side of the plate as shown by 12 and 13 in Fig. 1, and is then bent at an angle as indicated by 7' and again attached to the plate near its opposite side as indicated at 14. One or both of these attachments should be rigid, and the spring clasp is thereby firmly attached to the plate 2 and cannot move thereon nor turn in the points of attachment. The plate 2 also carries the hook 11, adapted to engage detachably the free end of the spring arm 8. When this spring arm is out of engagement with the hook 11, it will assume the position shown by the dotted lines 8' in Fig. 1. The arms 7 and 8 are bent at 9 and 10 as shown in Fig. 4, so that when the arm 8 is closed under the hook 11, the two bends 9 may encircle the post 15, and the two bends 10 approach each other and form a spring lock, normally holding the post against motion in the direction of plate 2, but at the same time yielding and

100

115

permitting the post to pass if sufficient force be applied.

The manner of using this device will be apparent from the drawings. The spring clasp 7 being open as shown in Fig. 4, and the post wholly disengaged therefrom, the upper free edge of the fabric to be supported is passed over the post 15 and its head 4, and the expanded circular portion of the 10 spring catch is then placed over and about the post, encircling the portion of the fabric which is carried by the post. The spring clasp is then closed by forcing the arm 8 into the locking engagement with hook 11. The 15 inward bends 10 of the arms thereby force the post into close engagement with the cushioned lug 5' and the fabric is firmly held in an elastic grip between the post and the cushion lug. As this cushion is so constructed, as shown in Fig. 2, as to cover also 20 the under surface of the lug, there will be similar cushioned contact affecting the fabric where it passes down between the lug 5' and the base of the post 15, so that there can be no abrasion of the fabric caused by rubbing between the two metallic surfaces.

By the use of this device I am enabled to avoid any sliding or rubbing of the fabric between the post and the walls of a surrounding guide or loop carrying the post to its seat at the narrow end of such guide; and the post is placed immediately, without such sliding contact, in the position which it is permanently to occupy. It will be noticed also, that the downward pull or weight of the supported fabric draws against the elastic or cushioned surface of the lug, instead of drawing against a metallic or rigid surface; and also that the double attachment of the clasp 7 to the plate 2 prevents the rotation which might otherwise occur, and thereby the spring arm 8 when closed is always at the proper point for engaging the hook 11.

From the foregoing it will be observed 45 that the clasp or clasp device is practically a part of the plate 2, as it is carried by said

plate and depends from the latter when the supporter is in use.

Having thus described my invention, what 50 I claim and desire to secure by Letters Patent is

1. In a hose supporter clasp, the combination of a pair of upper and lower plates each carrying an engagement member, the engagement member carried by the upper plate consisting of a spring clasp having a spring arm movable toward and from the center thereof, and having also an elastic cushion carried at the lower end thereof, and the engagement member carried by the lower plate consisting of a stud adapted to be embraced by the opposite portions of the spring clasp and held against the elastic cushion upon the spring clasp. 65

2. In a hose supporter, the combination of an upper plate carrying an engagement member, and a lower plate also carrying an engagement member to coöperate with the member of the upper plate, the engagement member carried by the upper plate consisting of a spring clasp provided with a spring arm, the upper plate having a hook with which the spring arm coöperates. 70

3. In a hose supporter clasp, the combination of a pair of upper and lower plates, each carrying an engagement member, the engagement member carried by the upper plate consisting of a spring clasp having a spring arm which may be opened and closed 75 and also having inward bends formed in opposite portions thereof to coöperate with the engagement member of the lower plate, whereby upward motion of the engagement member carried by the lower plate may be 80 resisted. 85

In testimony whereof I have hereunto set my hand in presence of two subscribing witnesses.

ROBERT B. TUNNICLIFFE.
